ATTORNEY

UNITED STATES PATENT OFFICE

WALDEMAR KROIER, OF TAMPA, FLORIDA

AWNING

Application filed November 6, 1931. Serial No. 573,466.

This invention relates to awnings and its general object is to provide an awning with ventilating means that is automatically operated, upon lowering and raising the awning but may be manually actuated if desired to opened or closed position, except when the awning is completely raised, as the ventilating means is then held in closed position to protect the awning from weather elements, the awning when completely raised or folded being entirely housed within a canopy which carries the ventilating means.

A further object of the invention is to provide an awning set forth, that is simple in construction, inexpensive to manufacture, easy to install, and extremely efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a perspective view of an awning constructed in accordance with the present invention and showing the same in applied position.

Figure 2 is a transverse sectional view taken through the canopy and the ventilating means carried thereby, with the ventilating means disposed in closed position in full lines, and open position in dotted lines.

Figure 3 is a fragmentary rear elevation of the canopy and the ventilating means.

Referring to the drawing in detail, the reference numeral 1 indicates a canopy which includes an inclined top provided with an elongated opening 2, the latter extending longitudinally of the top and terminating adjacent the ends thereof. The top has secured thereto in any well known manner or formed therewith side pieces 3 of substantially triangle formation and these side pieces are provided with flanges extending outwardly therefrom and disposed at right

angles with respect thereto as best shown in Figure 1. Arranged adjacent the bottom of the side pieces and extending from adjacent the forward ends thereof are slots 4. One slot is provided for each side piece and the slots are arranged in alignment for a purpose which will be presently apparent.

Pivotedly secured to the side pieces through the instrumentality of pivot pins 5 is a hood 6 which is substantially V-shape in cross section and includes converging walls merging together in rounded formation as will be noted upon inspection of Figure 2, and this hood also includes side pieces 7 through which passes the pivot pins 5. The side pieces have inwardly turned flanges 8 formed on the lower edges thereof, while their rear ends are cut away as at 9.

Extending across the canopy is a rod 10 which is provided with grooved rollers 11 mounted for rotation on the ends thereof, and these rollers are arranged in the slots 4 in a manner whereby the slots provide track-ways for the rod as will be apparent. Surrounding the rod 10 and mounted for rotation thereon is a sleeve 12 that is engageable with the flanges 8 of the side pieces 7 and by this construction, it will be apparent that movement of the rod in a rearward direction will cause the sleeve 12 to engage the flanges 8 and close the hood as shown in full lines in Figure 2. The rear ends of the slots 4 are directed upwardly, and when the rollers are disposed in the rear ends, the rod will be substantially fixed and held against movement for holding the hood in its closed position. In order to limit the movement of the hood in its open position, I provide a flexible member 13 which has one end secured to an eye 14 carried by the hood, while its opposite end is fastened to an eye 15 which is secured to the supporting means for the canopy, the supporting means being the front of a building or a strip of wood such as indicated by the reference numeral 16 that may be fixed to the front of the building in any well known manner.

The fabric portion of the awning is indicated by the reference numeral 17 and is of the usual construction, but has its side walls 100

18 secured to the side pieces 3 of the canopy while the upper edge of the front wall is fixed to the roller 11.

The top wall of the canopy is provided with a flange 19 for the purpose of receiving securing means for fixing the canopy to the strip 16, as shown in Figure 2, and I also provide reinforcing strips 20 arranged at intervals in the length of the canopy and which have one of their ends secured to the top wall and their opposite ends secured to the strip 16.

From the above description and disclosure of the drawing, it will be obvious that I have provided an awning which includes a ventilating means in the form of a hood carried by a canopy adapted to have fixed thereto the fabric portion of the awning, and when the fabric portion is in lowered position, the hood will be disposed to open position as shown in dotted lines in Figure 2, but when the fabric portion is in folded or closed position, the hood will likewise be closed. Due to the arrangement of the opening 2 in the canopy, it will be apparent that a room having a window therein with my awning attached to the latter, will be properly ventilated when the awning and hood are disposed in open position, and when the hood is arranged in open position as best shown in dotted lines in Figure 2, it acts in the capacity of a shield to prevent heated air from entering the room, as the heated air will be directed upwardly from the underside of the awning against the inside of the hood, thence outwardly through the opening 2, therefore the room is not only shaded by the awning, but heated air is practically eliminated therefrom.

The hood can be manually closed if desired but the hood will be automatically closed when the fabric portion of the awning is in folded or raised position, with the result the fabric portion will be protected from the weather elements.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. An awning of the character described comprising a canopy, a fabric portion having connection with said canopy, ventilating means carried by said canopy and means whereby the ventilating means is automatically operated upon raising and lowering the fabric means.

2. An awning of the character described comprising a canopy, a fabric means having connection with said canopy, ventilating means mounted for movement in said canopy and closing an opening formed therein, means having connection with the fabric means and

movable to close and allow for the opening of the ventilating means.

3. An awning of the character described comprising a canopy including an inclined top wall provided with an elongated opening, side pieces secured to the top wall and having slots arranged therein, a rod having its ends mounted for movement in the slots, a fabric means having connection with the rod and side pieces respectively, a hood pivotally secured to the side pieces and arranged in the path of the rod to be engaged thereby upon raising the fabric means to folded position to cause the hood to close the opening and said hood being movable to open position upon lowering the fabric means.

4. An awning of the character described comprising a canopy having an elongated opening formed therein, a hood pivotally secured in the canopy and being substantially V-shape in cross section, a rod extending across the canopy, grooved rollers mounted on the ends of the rod, said canopy being provided with slots forming track-ways for the groove rollers, fabric means included in said awning and being secured to the canopy and rod respectively, and said rod being movable upon raising and lowering the fabric means to automatically open and close the hood.

5. An awning of the character described comprising a canopy, a fabric portion having connection with said canopy, ventilating means carried by said canopy and being in the form of a hood controlling an elongated opening in said canopy, said hood being substantially V-shape in cross section, and being capable of closing said opening, and said hood when open acting in the capacity of a shield for directing heated air from the underside of said awning outwardly through said opening.

In testimony whereof I affix my signature.

WALDEMAR KROIER.
